SAFETY RAZOR BLADE STROPPER

Charles L. James, San Francisco, Calif.

Application July 1, 1935, Serial No. 29,279

7 Claims. (Cl. 51—153)

This invention relates to stropping devices for safety razor blades of the double-edged wafer type, and has for its objects improvements in such a stropping device as shown in my United States Patent No. 1,694,544, whereby its operation will be considerably improved and the sharpened blade will have keener edges. Other features and advantages of my improvements will appear in the following description and accompanying drawing.

In the drawing Fig. 1 is a side elevation of my stropper with blade and strop in position, and with part of the handle connection shown in section.

Fig. 2 is a plan view of Fig. 1.

Fig. 3 is an enlarged perspective view of the blade holding carriage of the stropper.

Fig. 4 is an enlarged end view of Fig. 3 showing the blade reversing swivel joint.

Fig. 5 is a fragmentary view partly in section, showing a modification of the universal joint which connects the handle to the frame of the stropper.

The stropper is very much like the one shown in my aforesaid patent for sharpening double-edged wafer blades, and likewise is of the type which is drawn back and forth on a strop by hand and automatically flips the leaving edge of the blade against the strop during one stroke, and the opposite edge during the next stroke, the blade-holding carriage being tilted first one way and then the opposite way by the friction of the strop acting on the carriage during its movement, the improvements herein relating to construction.

In the drawing the frame of the stropper comprises spaced sides 1 and a cross connecting plate 2 from which extends a detachable handle 3 which is connected to the cross connecting plate 40 of the frame by means of a universal joint 4 which will be more fully described at a later point in the specification. The sides of the frame are spaced by two round-shouldered pins or bars 5, and between the two pins 5 is a tiltable blade-holding carriage shown best in the detached view of Fig. 3.

This carriage has a pair of thin sheet metal hinged leaves 6, 7 between which the razor blade is adapted to be centered and clamped in the position shown at B in Figs. 1 and 2, and is firmly mounted on a round shaft 8 which passes freely through openings in opposite sides of the frame. The leaves are respectively perforated as at 9 and formed with bosses 10 for centering a safety 5 razor blade through the holes which exist in

the blades, and the leaves are hinged together at one end as indicated at 11 on a transversely extending pin 12 which passes loosely through a hole in the spherical upper end 13' of a small post 13 which revolvably extends through a hole 5 very close to the end of shaft 8 and has a head 14 to prevent it from pulling upward, while to prevent the post 13 pushing downward through the shaft the post 13 is necked or circumferentially grooved as at 15 within the shaft and the latter forced inward into the groove at one point, as by placing a center punch on the center of the shaft at 16 and striking it a light blow, or just sufficient to drive a small protuberance into the groove 15 of the post so that it will be held 10 in place against up and down movement yet be perfectly free to revolve.

It has been mentioned that the hinge pin 12 fits loosely in the hole in the upper ball end of the post, and this is to permit the blade clamping leaves 6 and 7 to rock transversely, or longitudinally, of hinge pin 12 for a purpose to be later explained.

The blade is placed between the leaves 6 and 7 and they are closed and their free ends dropped 25 into a notch in a bracket plate 17 rigidly secured to the opposite end of the shaft 8, as by riveting thereto, and a little latch bar 18 rather tightly pivoted at one end as at 19 to an ear 20 formed on plate 17 is closed across the notch and across 30 the reduced width projections or handle portions 7', 6' of the blade clamping leaves, and under a second ear 21 of bracket 17 so as to hold the leaves and blade together for stropping. However, a point to be observed here is that the 35 space under the latch bar 18 to accommodate the two extensions 6', 7' of the leaves is free or greater than their combined thickness when the blade is clamped between them, and this is to permit the same transverse rocking movement 40 of the blade clamping leaves at the handle end as is permitted at the hinged ends by the looseness of pin 12 in the hole in the ball 13'.

When the carriage is in place on the frame and blade B in position, and the strop, preferably a leather strap A extended or threaded through the frame between its sides 1 as shown in Figs. 1 and 2, and while holding the strop taut and moving the frame back and forth along the strop the friction of the latter on the upper side 50 of shaft 8 will rock or tilt the carriage in proper direction to bring the leaving edge of the blade against the strop so as to strop the same, and when the direction of the carriage is reversed it automatically forces the opposite edge down or 55

against the stropping surface, but due to the looseness of pin 12 in the hole in post ball 13' and the corresponding up and down freedom of the blade clamping leaves under latch bar 18, the leaves and blade can tilt slightly independently of their bodily tilting action on shaft 8 as a fulcrum, so that the blade flattens more to the plane of the stropping surface, to thus secure a somewhat longer bevel to the cutting edge.

10 The handle 3 is, as shown in Fig. 1, secured by a universal joint 4 to the cross connecting plate 2 of the frame and, as will be observed in Fig. 2, the point of attaching the handle is not in the center of the frame but considerably off center 15 so that when working the stropper back and forth the handle will be much closer to one edge of the strop A than to the other. This arrangement makes twist at an angle to the strop as indicated in Fig. 2 and gives an angular stropping action of the razor edge instead of maintaining it straight across the strop. Thus, with the strop- 20 per being moved by its handle in direction indicated by the arrow in Fig. 2, the opposite end of the frame will lag to the left, and will assume the opposite lag upon reversing the direction of travel. The handle being freely revolvable as 25 well as having a universal joint connection to the frame, does not communicate any twisting action of the hand to the stropper, but leaves it free to automatically assume the correct angle.

The handle may project either down or up, and the frame may be turned end for end so as to bring the handle at either side to suit either a left-handed or right-handed person.

30 35 The handle may be secured to the cross plate 2 of the frame by any desired form of universal joint, though in Fig. 1 the ball member is shown as having a neck 22 threaded on the outer end at 23 to screw into a threaded hole in the frame 40 and an enlarged shoulder or nut 24 which seats against the plate. The handle 3 is hollow on its upper end and crimped over the ball, and at the lower side of the ball is a square or hexagon projection 25 which is adapted to seat in a similarly formed socket 26 in the handle, all so that if the handle is pushed toward the frame it will slide over the neck 22 and the projection 25 will be engaged by the socket 26 so that upon then twisting the handle the ball member may be 45 screwed into or out of the plate.

50 In Fig. 5 the ball and socket members are reversed, the ball 4' being rigid on the handle 3' and the socket member 27 being part of the threaded piece 23' which screws into the plate 55 2. In this construction the socket member 27 may be made long enough to hold in the fingers to screw in place.

With either handle it is highly desirable to have the outer end 28 of the handle magnetized so 60 that the razor blade can be picked up from a flat hard surface such as a sink. The end of the handle is also preferably slotted as at 29 to provide north and south poles of the magnet.

65 In using the stropper it is first worked back and forth along the strop with the blade in the carriage, then the latch bolt 18 is opened, the blade clamping leaves are pinched at their extremities 6', 7', swung substantially vertical over post 13 and given a half turn, using post 13 as an 70 axis, to reverse the sides of the blade, and again lowered into the socket and fastened by latch 18 and stropped a few times more to sharpen the opposite sides of both edges.

Having thus described the nature of my im- 75 provements and the manner of operation, it will

be evident to anyone skilled in the art to which the invention appertains that various modifications of the preferred construction shown may be made within the spirit of the invention and scope of the appended claims.

5

I claim:

1. In a razor blade stropping device of the character described, a frame adapted to be slid back and forth along a strop, a tilttable blade-holding carriage mounted on the frame adapted 10 to present opposite edges successively to the strop surface in respectively opposite directions of travel of the device, and a handle for moving the device projecting from the frame, said handle connected to the frame by a ball joint, and said ball joint having one of its members threaded into the frame and the handle being longitudinally movable over the ball and provided with means for engaging said member for screwing the same in place.

20

2. In a razor blade stropper for wafer type razor blades, a frame provided with a handle and adapted to be slid back and forth along a strop, a tilttable carriage pivotally mounted on said frame for holding the blades, said carriage including a 25 pair of leaves hinged together at one end and to the carriage by a hinge pin extending transversely of the leaves with its axis centrally disposed with respect to the leaves and between which leaves the blades are clamped in position, 30 a latch on the carriage for holding the free ends of the leaves together when in operative position, and means at the hinged ends of the leaves arranged and adapted to permit bodily reversing of both leaves and blade to opposite operative 35 position when said latch is released, the arrangement being such that when the leaves are in either operative position the wafer blade will be the same distance from the strop.

35

3. In a razor blade stropper for wafer type 40 razor blades, a frame provided with a handle and adapted to be slid back and forth along a strop, a tilttable carriage pivotally mounted on said frame for holding the blades, said carriage including a pair of leaves hinged together at one end and to the carriage and between which leaves the blades are clamped in position, a latch on the carriage for holding the free ends of the leaves together when in operative position, and means at the hinged ends of 45 the leaves arranged and adapted to permit bodily reversing of both leaves and blade to opposite operative position when said latch is released, the arrangement being such that when the leaves are in either operative position, the then outermost leaf will swing outwardly on its hinge connection independent of the other leaf for release or insertion of a blade, the hinged connection of the blade clamping leaves to the carriage including a pin to which both leaves are hinged, a post 50 through which said pin passes, and means supporting said post for axial turning.

55

4. In a razor blade stropper for wafer type 60 razor blades, a frame provided with a handle and adapted to be slid back and forth along a strop, 6 a tilttable carriage pivotally mounted on said frame for holding the blades, said carriage including a pair of leaves hinged together at one end and to the carriage and between which leaves the blades are clamped in 7 position, a latch on the carriage for holding the free ends of the leaves together when in operative 7 position, and means at the hinged ends of the leaves arranged and adapted to permit bodily reversing of both leaves and blade to opposite 8

- operative position when said latch is released, the arrangement being such that when the leaves are in either operative position the then outermost leaf will swing outwardly on its hinge connection independent of the other leaf for release or insertion of a blade, the hinged connection of the blade clamping leaves to the carriage including a pin to which both leaves are hinged, a post through which said pin passes, and a shaft into 5 the side of which said post is rotatably supported, said shaft extending parallel to said leaves when clamping a blade, and a bracket plate secured to one end of said shaft and formed to cooperate with said latch in holding the free ends of said leaves.
5. In a razor blade stopper for wafer type razor blades, a frame provided with a handle and adapted to be slid back and forth along a strop, a tiltable carriage pivotally mounted on said frame for holding the blades, said carriage including a pair of leaves hingedly connected together at one end and to the carriage and between which leaves the blades are clamped in position, a latch on the carriage for holding the free ends of the leaves together when in operative position, and means at the hinged ends of the leaves arranged and adapted to permit bodily reversing of both leaves and blade to opposite operative position when said latch is released, the arrangement being such that when the leaves are in either operative position the then outermost leaf will swing outwardly on its hinge connection independent of the other leaf for release or insertion of a blade, the hinged connection of the blade clamping leaves to the carriage including a pin to which both leaves are hinged, a post through which said pin passes, a shaft into the 15 side of which said post is rotatably supported, said shaft extending parallel to said leaves when clamping a blade, a bracket plate secured to one end of said shaft and formed to cooperate with said latch in holding the free ends of said leaves, 20 said post passing into a hole in said shaft close to one end of the shaft and formed with a reduced neck within the shaft, and a head to the outer side of the shaft, and a center-punched indentation projecting from the shaft into said neck to 25 prevent withdrawal yet permit free turning of the post.
7. In a razor blade stopper for wafer type razor blades, a frame provided with a handle and adapted to be slid back and forth along a strop, 30 a tiltable carriage pivotally mounted on said frame for holding the blades, said carriage including a pair of leaves hingedly connected together at one end and to the carriage and between which leaves the blades are clamped in position, 35 a latch on the carriage for holding the free ends of the leaves together when in operative position, and means at the hinged ends of the leaves arranged and adapted to permit bodily reversing of both leaves and blade to opposite operative 40 position when said latch is released, the arrangement being such that when the leaves are in either operative position the then outermost leaf will swing outwardly on its hinge connection independent of the other leaf for release or insertion 45 of a blade, the hinged connection of the blade clamping leaves to the carriage including a pin to which both leaves are hinged, a post through which said pin passes, and means supporting said post for axial turning, and means to permit 50 limited free transverse tilting of said leaves when in operating position independent of the tilting of the carriage as a whole.
6. In a razor blade stopper for wafer type razor blades, a frame provided with a handle and adapted to be slid back and forth along a strop, a tiltable carriage pivotally mounted on said frame for holding the blades, said carriage including a pair of leaves hingedly connected together at one end and to the carriage and be-

CHARLES L. JAMES.
